HENRY K. AUSTIN, OF READING, MASSACHUSETTS.

TIRE-INFLATING PUMP.

1,335,718.

Specification of Letters Patent.

Patented Apr. 6, 1920.

Application filed April 11, 1919. Serial No. 289,296.

To all whom it may concern:

Be it known that I, HENRY K. AUSTIN, a citizen of the United States, residing at Reading, in the county of Middlesex and State of Massachusetts, have invented new and useful Improvements in Tire-Inflating Pumps, of which the following is a specification.

This invention relates to a tire-inflating pump of the type shown by my Patent No. 1,045,495, dated November 26, 1912, said patent disclosing a tire-inflating pump comprising a horizontally elongated base having a pump cylinder connected to one end portion, the other end portion having a horizontal passage communicating with the pump cylinder, and having also two vertical air chambers communicating with the horizontal passage, said chambers and passage being in the same vertical plane, said air chambers being provided with valve seats, valves in said chambers to coöperate with said seats, and a piston in said cylinder.

The invention is embodied in certain improvements in the pump base, whereby the said valves are adapted to be closed or seated by gravity aided by atmospheric pressure, without the aid of a spring or springs, and in the pump piston whereby its effectiveness is increased.

Of the accompanying drawings forming a part of this specification,—

Figure 1 is a side view.

Fig. 2 is a fragmentary view looking toward the side of the pump shown at the left of Fig. 1.

Fig. 3 is a section on line 3—3 of Fig. 2, showing the piston rising in the cylinder.

Fig. 4 is a view similar to Fig. 3, showing the piston descending in the cylinder.

Fig. 5 is a view similar to a portion of Fig. 4, showing the piston at the limit of its down stroke.

The same reference characters indicate the same parts in all of the figures.

In the drawings, 12 represents a pump cylinder, and 13 a piston of any suitable construction, movable in the cylinder, the piston being provided with a rod 14 having a handle 15. 16 represents a horizontally elongated base attached to the lower end of the cylinder, and having a bottom face adapted to bear on a supporting surface. In the cylinder is a main air conduit 17, communicating at one end with the cylinder and extending therefrom substantially parallel

with the bottom face of the base, one end 17^a of the conduit being offset upwardly, as shown by Figs. 3 and 4, and thus located above the valve seat of the inlet valve 18 chamber, next described. 18 represents an inlet valve chamber near one end of the base, said chamber being vertically elongated and perpendicular to the bottom face of the base, and communicating with the offset end 17^a of the main conduit. The valve chamber 18 is provided at its lower end with an upwardly facing valve seat 19, which is below the offset end 17^a.

20 represents an air inlet conduit of an angular form, communicating at one end with the lower end of the valve chamber 18, and at its opposite or intake end with the atmosphere, said intake end being in the upper portion of the base 16, and spaced from the bottom face of the latter, so that it is not liable to be obstructed by dirt. The upper end or head of the valve chamber 18 is formed by an imperforate plug 21, screwed into a tapped orifice in the base, said plug constituting a valve stop, located above the end 17^a of the main conduit, and arranged to permit the inlet valve 26, hereinafter described, to rise above the end 17^a, as shown by Fig. 3.

22 represents an outlet valve chamber, communicating at its lower end with the main conduit 17 between the inlet valve chamber 18 and the cylinder 12. The valve chamber 22 is perpendicular to the bottom face of the base, and is provided at its lower end with an upwardly facing valve seat 23.

24 represents a nipple screwed into a tapped orifice in the base and forming a valve stop at the upper end of the outlet valve chamber 22, said nipple being provided with a flexible conduit 25 adapted at its outer end to be coupled to a tire valve.

26 represents an inlet valve which is weighted and adapted to be closed by gravity on the seat 19 of the inlet valve chamber, and provided with a guiding stem 27, which is movable in and guided by a portion of the air inlet conduit 20.

28 represents an outlet valve adapted to be closed by gravity on the seat 23 of the outlet valve chamber, and provided with a guiding stem 29, which is movable in and guided by the branch conduit 30 which connects the valve chamber 22 with the main conduit 17.

When the piston 13 is rising, air is drawn

through the inlet conduit 20, and raises the inlet valve 26 to the stop provided by the plug 21, so that air is permitted to pass freely to the main conduit 17, as shown by Fig. 3, the outlet valve 28 being at the same time held upon its seat by gravity, aided by suction in the main conduit 17, so that the cylinder 12 is filled with air below the piston. When the piston is descending, the 10 weighted inlet valve 26 is seated and held upon its seat by gravity, the outlet valve 28 being at the same time raised to contact with the stop formed by the inner end of the nipple 24. The nipple is provided with 15 radial grooves 31 in its inner end face, said grooves permitting air to pass from the valve chamber 22 to the nipple, when the valve 28 is raised, as shown by Fig. 4.

The chief novelty in the structure thus far described resides in the vertically elongated inlet valve chamber 18, having the upwardly facing valve seat 19 at its lower end and the imperforate plug or valve stop 21 at its upper end, the air inlet conduit 20 20 communicating with the chamber 18 below the valve seat, the weighted valve 26, closed by gravity on the seat 19, the main air conduit 17, 17^a, communicating with the chamber above the valve seat, the imperforate 25 plug 21 being arranged to permit the valve to rise above the intake end of the main air conduit, and thus permit air to pass freely 30 to the cylinder.

The base 16 is provided at opposite sides 35 with ears 32, projecting laterally from the base and cylinder. To said ears are connected by pivot-pins 33, two foot rests 34, which are adapted to bear on a supporting surface at opposite sides of the base and be 40 engaged by both feet of the person operating the pump, said rests being foldable against opposite sides of the cylinder, as indicated by dotted lines in Fig. 2.

The pump piston includes two flanged or 45 cupped flexible members or cup-washers 13^a of leather, or other suitable material, arranged at opposite sides of a metal washer 36, the annular flanges 13^a of the cup-washers projecting in opposite directions, and the 50 central portions of the cup-washers being clamped between the central washer 36 and nuts 37 engaged with a threaded portion of the piston rod 14. The annular flanges 13^a are liable to shrink or contract, so that they 55 do not contact effectively with the interior of the cylinder, the result being a leakage of air between the piston and cylinder when the pump is in operation. To enable the operator to expand or set out the flanges 13^a, whenever this is needed to overcome leakage, I provide the piston with two flange-expanding rings 39, each of which is a metal ring, preferably of sheet metal, contracted 60 at its inner edge to form an inwardly projecting lip 39^a. Said lips loosely em-

brace the nuts 37, and are adapted to slip thereon, so that the expanding rings 39 are movable into and out of the flanges 13^a of the cup-washers. Stops 40 fixed to the piston rod, limit the outward movements of 70 the said rings. The external form of the expanding rings 39 is such that when they are forced into the space surrounded by the flanges 13^a, they expand or set out said flanges, sufficiently to prevent leakage of air. 75 The lips 39^a of said rings are normally in contact with the stops 40, so that the rings do not exert expanding pressure on the washer flanges 13^a, unless they are forced into said flanges. 80

In case the operator finds that there is a leakage of air between the piston and cylinder, he increases the down stroke of the piston to cause the lower expanding ring 39 to contact with the pump base and force 85 said ring into the flange of the lower cup-washer, as shown by Fig. 5, and increases the upward stroke of the piston to cause the upper expanding ring 39 to contact with the head 43 of the cylinder and force said ring 90 into the flange of the upper cup-washer. The expanding rings 39 do not remain in positive expanding contact with the flanges 13^a, but work outwardly during the ordinary 95 operation of the pump, until the operator again forces them into positive expanding contact by increasing the length of the stroke of the piston. It is obvious that in case the piston has only one cup-washer, only one expanding ring 39 will be required. 100

I claim:

1. A tire-inflating pump comprising a cylinder, a piston therein, a horizontally elongated base attached to the lower end of the cylinder and projecting from one side 105 of the latter, said base having a longitudinal main air conduit communicating at one end with the cylinder, a vertically elongated inlet valve chamber in the outer end portion of said base, having an upwardly facing 110 valve seat at its lower end, and communicating above said valve seat with the opposite end of the main air conduit, an air inlet conduit in the base communicating at one end with the atmosphere, and at the other 115 end with the inlet valve chamber, below the valve seat in the latter, an inlet valve movable vertically in the inlet valve chamber, and weighted to normally close by gravity 120 on the seat of said chamber, the inlet valve being raised by suction in the main air conduit when the piston is rising, and an imperforate plug closing the upper end of the inlet valve chamber, and forming a stop arranged to permit the inlet valve to rise above 125 the main air conduit, so that free passage of air from the inlet air conduit to the main air conduit is permitted when the inlet valve is raised, the said base being provided with an outlet valve chamber communicating with 130

the main air conduit between the inlet valve chamber and the cylinder, and with an outlet valve in said outlet valve chamber, opened by pressure in the main conduit when the piston is descending, and closed both by gravity and by suction in the main conduit when the piston is rising.

2. A tire-inflating pump comprising a base, a cylinder opening at its lower end into the base and having a head at its upper end, a piston movable in the cylinder and including a pair of flexible cup-washers hav-

ing annular flanges, a piston-rod to which said washers are attached, and a pair of flange-expanding rings loosely connected 15 with the piston and adapted to be forced by extended movements of the piston into contact, one with the base, and the other with the cylinder head, to expand said flanges, the piston being provided with stops limiting the movements of said rings. 20

In testimony whereof I have affixed my signature.

HENRY K. AUSTIN.
